UNITED STATES PATENT OFFICE.

PAUL GULLUNG, OF ST. ETIENNE DU ROUVRAY, FRANCE.

CARD-STOPPING DEVICE.

Application filed February 10, 1928, Serial No. 253,470, and in France February 14, 1927.

In carding machines for cotton and other textile materials, in order to avoid non-uniform operation and to produce an unobjectionable quality of material, it is necessary that the machine be stopped instantly upon the occurrence of any disturbance of the operation. This is particularly important when:

1. The fleece breaks between the feed rolls and the drawing-off rolls;
2. The silver breaks between the drawing-off rolls and the head of the can;
3. The cord driving the doffer falls off or breaks;
4. A too heavy or too thin layer of the material being treated is passed through the card, and
5. The carding can is too full and the head of the can is lifted off by the pressure of the cotton.

It is already known, in order to avoid these difficulties, to provide between the feed rolls and the drawing-off rolls a feeler which ordinarily lies against the fleece and which, upon breaking or irregular feeding of the fleece, executes an oscillatory movement and thereby effects the closing of an electric circuit wherein an audible or other signal is included. This arrangement, however, has the disadvantage that when a disturbance of the operation occurs, the result is not to stop the card automatically, but merely to call the attention of the operator tending the machine to such disturbance, so that a certain amount of time passes before the stopping of the machine by the operator. It has also been proposed to arrange a solenoid in the electric circuit which operates upon the stop mechanism of the card in such a manner that the card is stopped upon closing of the circuit; but this arrangement, as a rule, is likewise unsuitable, since it requires the use of a source of current, and the conductivity of the exposed contact levers is injured by the cotton fibers settling thereon, so that in spite of the actuation of the feeler the closing of the circuit often does not take place.

According to the present invention, the disadvantages specified are overcome by utilizing the movement of a feeler located between the drawing-off rolls and the head of the can to enable the stop mechanism of the card to be actuated in a purely mechanical fashion, for example, by means of a Bowden wire, whereby a certain and instanta-

neous interruption of the operation is attained.

In the preferred form of the invention, a plunger subjected to the pressure of a spring or the like is connected by a Bowden wire to the stop mechanism of the card, so that upon movement of the feeler said plunger is freed and imposes a tension upon the Bowden wire.

The arrangement according to the invention has, as a result of its small size, the particular advantage that it may be applied in a very short time and without difficulty to cards of any construction whatever, and that its actuation may control any desired stop mechanism.

In the accompanying drawings:

Figure 1 is a view, partly in section, showing the releasing mechanism or device that cooperates with the feeler, the parts being in set position;

Fig. 2 is an end view of Fig. 1;

Figs. 3 and 3^a are side and end views, respectively, of a connection between the Bowden wire and the stop lever of the machine;

Figs. 4 and 4^a are similar views of a modified connection;

Fig. 5 shows a device for throwing out of gear the drive shaft of the feed rolls of a card;

Fig. 6 is a modification of the device shown in Fig. 1;

Fig. 7 shows the invention in use.

In Figs. 1, 2 and 7, 24 is a feeler secured to the upper end of a rod 22, over which the sliver 40, coming from the drawing-off rolls 41 of a card 42 of any desired construction, is led before its entry into the can 43. The lower end of the rod 22 carrying the feeler 24 is threaded into a forked lever 20 pivoted on a pin 6 mounted in lateral projections on a casing 17. In this casing is arranged a plunger 2, which is subjected to the pressure of a spring 1 and may be pushed downwardly against the action of the spring by means of a handle 3 that projects through a slot in the casing.

A setting plate 16 is cast on the plunger casing 17 and is provided with two longitudinal slots 18, through which latter pass two screws 19 by means of which it is adjustably attached to the standard or column 44 at the side of the can 43 (Fig. 7).

In the upper end of the plunger 2 is seated a ball 4, which cooperates with the upper end or toe of a latch 5 also pivoted on pin 6; the

lower end or heel of the latch being engaged by a leaf spring 7, which is secured by a screw 8 to the casing 17. In the position shown in Fig. 1, the plunger 2 is prevented from upward movement by the latch 5, so that the device remains under tension. The tensioning of the spring 1 may be effected by means of a threaded plug 9 having a central bore 10 through which the cable 11 of a Bowden wire 10 is passed; the upper end of said cable extending through the plunger 2 and being secured to a ball 13 which lies in a seat in the top face of the plunger. The sheath 12 of the Bowden wire is secured to the under side of 15 the plug 9.

A second threaded plug 14 is screwed into the upper end of the casing 17 and has formed in its under side an annular groove 15 which serves, in the extreme outward or upper position of the plunger 2, to receive the ball 4; the plug 14 acting to limit the stroke of the plunger.

The forked lever 20 mounted on pin 6 is provided with an arcuate projection or finger 25 21 which is adapted to strike against the heel of the latch 5 upon a clockwise rocking movement of the feeler, so that the latch is turned about said pin 6 against the action of spring 7 and thereby releases the plunger 2. The 30 Bowden wire secured to the plunger is so combined with the stop motion of the card that, upon upward movement of the plunger, the stop lever is actuated and the operation is interrupted, and in accordance with the 35 arrangement of the stop mechanism either the drive for the feeding rolls or the drive for the doffer may be stopped. In the arrangements shown in Figs. 3, 3^a, 4 and 4^a, the actuation of the Bowden wire will lift or pull 40 down the stop lever.

In Figs. 3 and 3^a, 25 is the stop lever of the card, the operation of which releases a movable projection 28, which, by its movement, effects the stopping of the doffer and the feed 45 in any desired known manner. Immediately adjacent the lever 25 is arranged a hook-shaped slide rod 27 guided in a bracket 26, the hook part of which rod underlies said lever 25, as shown. At the upper end of the 50 slide rod 27 is secured the cable 11 of the Bowden wire, so that by pulling said cable upward the lever 25 will be lifted and the projection 28 released.

Figs. 4 and 4^a show a modification in which 55 the stoppage of the doffer is effected by rotation of the shaft of stop lever 31. The sheath 12 of the Bowden wire is here secured by nuts 30 to an angle bracket 29 arranged in suitable manner on the frame of the card. The end 60 of the cable 11 is anchored by means of a clamping screw 33 in a hole formed in a roller 32 carried by said lever.

Whereas in the arrangements shown in 65 Figs. 3, 3^a, 4 and 4^a, the operation involves the throwing out of the doffer, Fig. 5 illustrates

an arrangement wherein the rotation of the drive shaft of the feed rolls is to be interrupted as soon as a tension is exerted upon the Bowden wire. The end of the cable 11 in this arrangement is secured to a movable 70 pin 35 disposed within a housing 34, which pin is normally pressed downward by a spring 36 and, in the position shown, holds two bevel gears 38 and 39 comprised in the feed roll drive in engagement with each 75 other. The housing 34 is screwed into the top of the bearing box of the feed roll shaft and is closed at its upper end by a cover 37. When an upward pull is exerted upon cable 11, the rod 35 is also drawn upward against 80 the action of the spring 36, so that the drive wheels 38 and 39 are disengaged by the action of a spring (not shown), or in any other suitable way, and the feed is thereby stopped.

The operation of the entire arrangement is 85 as follows: The feeler 24, so long as there are no disturbances in the operation of the machine, is maintained in position by the tension of the sliver 27 running over it. As soon, however, as the sliver breaks or acquires a diameter less than that desired, the feeler 24 is caused to rock about its pivot 6, thereby bringing its arcuate finger 21 into contact with the latch 5 and swinging it about said pivot. The result thereof is that the plunger 2 is released 90 and moves upwardly under the pressure of spring 1, whereby the cable 11 is pulled upward and the stop lever 25 or 31 is actuated. After the stopping of the card, the plunger 2 may again be retracted and tensioned by 95 means of the handle 3 or in some other manner.

The embodiment shown in Fig. 6 differs from that of Figs. 1 and 2 in that in place of the latch 5, two latches 5', 5'' are provided; latch 5'' being pivoted on pin 6, and latch 5' on pin 6', the first-mentioned latch having a projection T' for holding the plunger 2 in tensioned position. Upon movement of the feeler secured to the forked lever 20, the latch 5'' is struck and turned about pivot 6' by finger 21, whereby lever 5' is rocked about pivot 6', so that projection T' is withdrawn from engagement with the top of plunger 2, which latter is thus released.

I claim as my invention:—

1. In a carding machine, a movable controller, a feeler subjected to the tension of the sliver, a spring-actuated plunger, a flexible element directly connecting the plunger to the controller to actuate the latter consequent on active movement of the plunger, a detent normally holding said plunger in inactive position, and a member connected to move with the feeler when the tension imposed thereon falls; said member, in its movement, adapted to strike against the detent and thereby release the plunger for movement by its spring.

2. In a carding machine equipped with a stop motion which includes a stop lever, a trip 130

- mechanism for the stop lever comprising a feeler subjected to the tension of the sliver, a spring-actuated plunger, a flexible element directly connecting the plunger to the stop lever to actuate the latter consequent on active movement of the plunger, a detent normally holding said plunger in retracted position, and a member connected to move with the feeler when the tension imposed thereon falls; 5 said member, in its movement, adapted to strike against the detent and thereby release the plunger for movement by its spring.
3. In a carding machine, a movable controller, a feeler subjected to the tension of the sliver, a hollow casing having a slot in its side wall, an external cross-pin attached to said wall opposite said slot and to which the feeler is pivotally connected, a spring-actuated plunger movable in said casing, detent means 10 pivotally mounted on said pin and projecting through the slot into the casing to engage the plunger and hold it normally in retracted position, a flexible element directly connecting the plunger to the controller to actuate the 15 latter consequent on active movement of the
- plunger, and a member connected to move with the feeler when the tension imposed thereon falls; said member, in its movement, adapted to strike said detent means and thereby release the plunger for movement by its spring. 20
4. A machine according to claim 1, in which both the feeler and the striking member are attached to a pivotally-mounted support. 25
5. A machine according to claim 3, in which a forked lever is pivoted to the cross-pin carried by the plunger casing and to which both the feeler and the striking member are directly attached. 30
6. A machine according to claim 3, in which a forked lever is pivoted to the cross-pin carried by the plunger casing and to which both the feeler and the striking member are directly attached, said striking member having the form of an arcuate finger secured at one end to the forked lever and adapted to strike the detent means with its free end. 35

In testimony whereof I affix my signature.

PAUL GULLUNG.
